UNITED STATES PATENT OFFICE

116,412

DESIGN FOR A PENCIL TIP

Joseph S. Reckford, New York, and Edwin C. Kubler, Hollis, N. Y., assignors to American Lead Pencil Company, Hoboken, N. J., a corporation of New York

Application June 28, 1939, Serial No. 85,732

Term of patent 7 years

To all whom it may concern:

Be it known that we, Joseph S. Reckford and Edwin C. Kubler, citizens of the United States, residing, respectively, at 888 Park Avenue, New York city, in the county of New York and State of New York, and at 186-40 Hilburne Avenue, Hollis, in the county of Queens and State of New York, have invented a new, original, and ornamental Design for a Pencil Tip, of which the following is a specification, reference being had to the accompanying drawing, forming part thereof.

We claim:

The ornamental design for a pencil tip, substantially as shown.

JOSEPH S. RECKFORD.
EDWIN C. KUBLER.
